UNITED STATES PATENT OFFICE

2,538,014

FREEZER PLATE

Herman W. Kleist, Chicago, Ill., assignor to Dole
Refrigerating Company, Chicago, Ill., a corpora-
tion of Illinois

Application May 5, 1947, Serial No. 745,929

2 Claims. (Cl. 257—256)

1

My invention relates to an improvement in refrigerator plates, and has for one purpose to provide an improved plate for supporting food, for example, during the freezing process.

Another purpose is to provide a plate which may be made in substantial lengths, while maintaining true plane surfaces on both sides of the plate.

Another purpose is to provide a vacuum plate having an improved header and evaporator duct or tube structure.

Another purpose is to provide a plate of the type above described, which includes integral reinforcing means along opposite edges.

Another purpose is to provide a plate particularly adapted for the freezing of materials, such as foodstuffs, and for the handling or movement of materials during or in connection with the freezing operation.

Another purpose is to provide a plate particularly adapted for use with materials which are moved longitudinally along the plate.

Other purposes will appear from time to time in the course of the specification and claims.

The present application is an improvement on the structure of my co-pending application 655-338, filed March 18, 1946, and now issued Patent 2,436,390.

I illustrate my invention more or less diagrammatically in the accompanying drawings 30 wherein:

Figure 1 is a plan view with parts broken away and parts in section;

Figure 2 is an end elevation of a plate;

Figure 3 is an enlarged section taken on line 35 3—3 of Figure 1;

Figure 4 is a partial side elevation on an enlarged scale;

Figure 5 is an enlarged section taken on line 5—5 of Figure 1; and

Figure 6 is a partial section illustrating a variant form.

Referring to the drawings, I illustrate a plate structure which includes a central plane sided portion A with an enlarged header enclosing structure B extending along each of two opposite edges of the plate, and including or surrounding a pair of spaced header structure. It will be understood that the enlarged structure constitutes a reinforcement for the plate, providing parallel reinforcements along each of two opposite edges. It will further be understood that these edge enlargements constitute side walls or limit members which prevent the unintended lateral escape of material undergoing treatment, and define a longitudinally extending trough.

2

With particular reference to the structure shown, I illustrate headers 1 and 2. In Figure 3 these headers are illustrated as cylindrical in cross-section. In the form of Figure 6 these headers, indicated at 1a or 2a, are shown as rectangular in form. 3 indicates an inlet extending to the header 1, and 4 indicates an outlet extending from the header 2. So far as the structure is concerned, the relationship can be reversed and each of the members 3 or 4 can be used either as an inlet or as an outlet. For convenience of description, however, I will call the member 3 the inlet and the member 4 the outlet.

The headers are connected by a system of 15 evaporator tubes or ducts which are arranged in parallel. These tubes, indicated at 5, are preferably rectangular in cross-section, having opposite plane walls 6 and 7, which are parallel with the later described plane face of the plate, 20 and which are connected by side walls 8 and 9. Each evaporator duct 5 is provided with a bend 10 connecting an initial length 11 with an intermediate length 12. The opposite end of the intermediate length 12 is connected by a bend 13 with a terminal length 14. Whereas these ducts 25 may be arranged in various ways, I find it advantageous to have the intermediate lengths 12 extend in parallel along the length of the plate. The initial lengths 11 are shown as extending generally perpendicularly from the header 1, whereas the final lengths 14 are shown as extending generally perpendicularly to the header 2. It will be understood that the outer surface of all of the tube walls 6 are formed or constrained to a single common plane, the same being true of the outer surfaces of the opposite walls 7.

I have described an evaporator structure, and it will be understood that a volatile refrigerant in liquid form, or, at least, only partly evaporated, 40 may be delivered to the header 1 along the inlet duct or tube 3. The refrigerant then passes in parallel through the evaporator ducts 5 to the opposite header 2, and the partly or completely evaporated refrigerant escapes through the outlet 4. Any suitable means, not herein shown, 45 may be employed for circulating or cycling a volatile refrigerant through the above described evaporator and header structure. I may employ any suitable mechanical compressor-condenser assembly, or I may employ any other suitable means for maintaining the desired flow of the volatile refrigerant through the evaporator ducts 5.

In order to provide the final plate, I house or 55 enclose the above described evaporator structure in an outer housing. I illustrate, for example,

opposite plate walls 20 and 21 which extend to and are connected to header surrounding housings or members 22 and 23. Each such header housing is shown as generally rectangular in cross-section. I find it practical and efficient to form the plate and header structure by employing unitary sheets which extend from side to side of the plate. Thus the plate wall 21 is continuous with and forms part of a single sheet of material which is bent to form corners 24, 25 and 26, and which terminates in an outward flange 27. The plate wall 20 is similarly formed, with angles or corners 24a, 25a and 26a and a terminal flange 27a. The flanges 27 and 27a are welded or otherwise secured in liquid and gas-tight relationship. Corresponding flanges 28 and 29a, at the ends of the plate, are similarly welded. The end result is a plate structure, surrounding the evaporator, which is liquid and gas-tight, in which both the headers 1, 2, and the evaporator ducts 5 are enclosed.

I may use one or more vacuum fittings 30 through which the air in the interior of the plate may be partly exhausted. As the air is withdrawn, the differential of pressure between the outside atmosphere and the inside of the plate is effective to urge the walls 20 and 21 firmly against the opposed outer plane surfaces of the duct walls 6 and 7. It will be understood that, before assembling the surrounding plate structure, the ducts 5, if not already true, are carefully trued, so that the outer surfaces of the walls 6 and 7 come very close to lying in a single plane. As the air is exhausted from inside of the plate, the thrust of the atmospheric air is effective to lock the sheets or walls 20 and 21 firmly against the opposite faces of the ducts 5. The result is a smooth-faced, true-surfaced plate, which is plane from end to end, but which is reenforced by an enlargement or a thickening along each of two opposite edges. The thickening or enlargement performs the double function of reenforcing and truing the plate and of serving as a limit or wall to prevent the undesired lateral escape of material across the edges of the plate, when the plate is used in a generally horizontal or somewhat inclined position for the handling or conveying of material in connection with or during the freezing operation.

It will be realized that, whereas, I have described and illustrated a practical and operative device, nevertheless, many changes may be made in the size, shape, number and disposition of parts without departing from the spirit of my invention. I therefore wish my description and drawings to be taken as in a broad sense illustrative or diagrammatic, rather than as limiting me to my precise showing.

The use and operation of my invention are as follows:

The above described plate may be used in a wide variety of sizes and shapes. A useful application of the invention is to a plate which is substantially longer than it is wide. Such a plate may, for example, be employed as a conveyor or a chute for material undergoing treatment. It may be positioned, either horizontally or at an angle to the horizontal. Material may be conveyed gravitally or mechanically along the length of the plate. Any suitable conveying means, knives, flights or the like, not herein shown, may also be employed, if desired, to convey material along the plate and between the edge enlargements.

The employment of two parallel headers, with the connecting sequence of ducts 5, constitutes, with the outside plates, a strong, reinforced and substantially rigid structure, which will maintain a true plane surface throughout a very substantial length.

It will be understood, of course, that these plates may be used in groups, arranged in parallel or in series, with any suitable system or means for circulating or cycling a refrigerant, preferably a volatile refrigerant, through the ducts 5.

A practical application of my invention is to employ one or more of the above described plates, set at an angle to permit or cause a gravitational movement of material to be cooled or frozen. Where a liquid such as milk is being cooled, a slight inclination may be sufficient, but where foodstuffs or liquids are being frozen, a substantial angle may be necessary in order to maintain gravitational feed or movement of solids.

I claim:

1. In a cold plate adapted to maintain a substantially true plane surface over a substantial area and throughout wide temperature variations, 25 an outer housing including spaced, parallel plane flexible sheet metal top and bottom walls sealed together about their side and end edges, an evaporator structure in the space surrounded by said 30 walls, including headers extending generally parallel and adjacent the opposite side edges of the plate and evaporator tubes extending between said headers, each said evaporator tube having an end portion extending from one header, an opposite 35 end portion extending from the other header a, a connecting intermediate portion, the evaporator tubes having throughout their length flat parallel surfaces opposed to the inner faces of both said top and bottom walls, the evaporator tubes being 40 uniformly spaced, the ends of each tube being uniformly offset, said tubes being of generally uniform length and being bent intermediate their end portions, said bends being generally aligned, 45 the end portions decreasing in length inwardly from each of the end edges of the plate, whereby each tube is adapted to flex in response to temperature changes without varying the distance between headers or the distance between said top and bottom walls, an inlet pipe extending to one header and an outlet pipe extending to the other said header, the headers and evaporator tubes constituting reinforcements for the housing, and means for maintaining a less than atmospheric air pressure in the housing whereby, in 55 response to such pressure differential, the flexible top and bottom walls are firmly held against the opposed flat surfaces of the evaporator tubes.

2. The structure of claim 1 characterized by and including enlarged opposite plate edge portions 60 extending along the side edges of the plate, the headers being located in said enlarged portions.

HERMAN W. KLEIST.
